UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIO BROADCAST DISTRIBUTING SYSTEM.

Application filed December 6, 1924. Serial No. 754,406.

My invention relates to systems of radio broadcast distribution, and has for its object to organize such a system so that programs may be originated, relayed, and distributed over a wide area, in a systematic and orderly manner; so that ultimate receiving stations may be controlled and operated as subscribers' stations and the programs distributed may be confined to said subscribers' stations and not be available for outside receiving stations not forming a part of the system; so that subscribers may select different programs or different items from different programs as time of rendition proceeds; so that subscribers may obtain any item produced and distributed from any part of the system to any other part of the system and within the range of their selective apparatus; so that while the subscribers may get the full benefit of amplification and the use of vacuum tubes in receiving and amplifying, yet their stations will be tubeless, that is to say, all the tubes pertaining to subscriber's receiving apparatus shall be located at central points, which may be also the final distributing points through which the programs or signals are given to the subscribers; so that all reception by the subscriber of programs or program items selected by him, shall be differentially metered according to the value fixed upon them by the broadcasting authorities, and automatically recorded at the rates so determined; so that a subscriber may have nothing at his station but standard telephone apparatus, connected and operating in conjunction with telephone line circuits, but capable of operating a loud speaker when desired; and finally so that the entire control, supervision, metering, current supply, installation and maintenance of subscribers' instruments will be from organized central stations provided with expert operators.

I attain these and other objects which will sufficiently appear hereinafter by connecting all the subscribers' stations in groups to localized central offices or exchanges, providing such exchanges with receiving instruments which may be of any suitable type, such as those described in my prior copending application, Serial No. 746,357, filed October 28, 1924, patented July 5, 1927, No. 1,635,153; providing line circuits entering a central station with vacuum tubes, one for each line, constituting terminals of the lines for radio distribution; and finally connecting these distributing tubes, which may be audio frequency amplifiers, to the output terminals of the appropriate receiving devices, and employing these connections as well as the conditions brought about by the subscribers, to operate meters, and to enable the central office operators to variously control, supervise, etc.

In my prior application aforesaid, distribution to the subscribers is by means of pure radio waves radiated from C or local distributing stations, which in turn receive radio or wire communications from so-called B or district stations, and so on to a master station designated as A. In the system described in said application, provision is made for alternative distribution throughout the system by wire or by radio, and for using long waves or intermediate frequencies for carrying the audio modulations, these intermediate frequencies or long waves being then transmitted either by wire carriers or as modulations on high frequency or short radio carrier waves. In other words, the original modulations, unchanged, are passed along and relayed from point of origin, on their long carrier waves, to the ultimate points of reception, being multiplied and amplified on the way so that all transmission losses are neutralized or compensated, and the subscribers with very simple and inexpensive instruments can receive from all points, near or far, as efficiently as though they had the best and most powerful receiving instruments available. It is the purpose of the present invention to carry this a step farther, by making it possible for absolute uniformity to be obtained in the efficiency of distribution and ultimate receiving, as well as the greatest economy in apparatus, costs of installation and maintenance, and cost of service. I do this by distributing over the subscriber's wire lines, at audio frequencies, and determining the volume of current and the efficiency of transmission over each line individually, by using a line valve or tube at the central station. For selective purposes, the subscriber is provided with a dial or other means of producing impulses or the equivalent in his line, and at the central station a simple switch is associated with each line, to connect the input side of the line tube with any desired program bus or receiving instrument at the

central office. These connections may be varied by the subscriber controlling his switch, from moment to moment and from item to item on the program, as desired. 5 Where there are a number of programs receiving simultaneously, the common batteries at the central office may be divided into groups, one for each program, so that only those subscribers' lines will be tied together, 10 even through their tubes, which are taking the same program. Cross talk or leakage from line to line is thus avoided.

This invention is applicable to manual, 15 automatic or so-called semi-automatic or automatic telephone systems, as will sufficiently appear hereinafter. The main underlying principle involved is that of relaying at the local central stations from one or more receiving instruments to a plurality 20 of subscribers' lines by means of individual line tubes or valves, so that each line may have its own self contained receiving unit, needing only excitation by the central office relay transmitter.

25 The method I have found most satisfactory in practice is to include one stage of audio amplification in each central office relay set or transmitter, the line tubes constituting a second stage. Current carrying capacity and power of the line tubes may be varied within wide limits, affording any amount of energy for transmission and any class of service that is desired. If the exciting circuits connected to any one bus at 30 one time are too many, the busses may be banked by means of tubes in parallel as well understood in the art. In this case, each central office receiver supplying a bus would preferably have a detector tube connected 35 through a transformer to a plurality of audio amplifier tubes in parallel, constituting a multiplied first stage, the plate circuits of which would be connected to the bus through a suitable transformer.

40 45 Regulation of the current flow from the B or plate battery through each bus during program transmission may be obtained by means known in the art and usually manipulated by an operator at a transmitting station.

50 Some modifications can be made in the arrangement and many modifications in the detail of circuit and design, but I feel the principle as stated to be novel in its application and original with myself, and I shall claim the same accordingly.

55 My invention is illustrated in the accompanying drawings, in which:

60 Figs. 1 and 2 indicate, diagrammatically, the telephone exchange portion, and broadcast distributing portion, respectively, of my combined telephone exchange and broadcast distributing system.

65 Fig. 3 is a modification of the circuit arrangement of Fig. 2.

Fig. 4 is a modified form of the switch arrangement of Fig. 3.

Fig. 5 is a diagram showing the operative relation and connections between different stations in a general system of broadcast distribution embodying the invention. 70

Fig. 6 is a diagram of a trunking arrangement for extending a subscriber's line circuit outside the local central station.

Fig. 7 is a schematic diagram showing the general arrangement for distribution of a broadcast program through an amplifier circuit common to a plurality of lines and second stage amplifier tubes and circuits individual to the subscriber's line. 75

Referring to the drawings in detail, and first to Fig. 1, this shows the essential circuits of an ordinary telephone exchange system in which A' is a subscriber's station connected by line wires 69—70, to the central station C where they terminate on multiple jacks J'. Similarly the multiple jacks J at the left of the figure represent the terminals of another substation line. These jacks are arranged to be interconnected through the usual answering and calling plugs P—P' forming the terminals of the usual common battery cord circuit shown. The central office terminals of each line are provided with the usual line relay L¹, line lamp L² and cut-off relay L³. Where service is to be metered a recording meter M is also individually associated with the line. Thus, the circuit arrangement here shown is that of the standard multiple switchboard, common battery, telephone exchange system, and as such is well understood in the art further detailed description thereof will be here deferred and brought out later in the description of operation. In addition to the usual line terminal multiples 1, 2 and 3, representing multiples of the tip, ring and test or cut-off circuits, respectively, I provide a fourth conductor 4 leading from a contact on the line relay along with the multiple conductors 1, 2 and 3 to the broadcast distributing system diagrammed in Fig. 2. 90 95 100 105

Fig. 2 shows the broadcast distributing system of which the portion to the left of the dotted line is situated at the central office and connected with the subscriber's telephone line terminal apparatus of the telephone central C (Fig. 1) through conductors, 1, 2, 3 and 4, while the portion to the right of the dotted line in Fig. 2 is situated at the subscriber's substation and connected with the subscriber's telephone substation apparatus A' (Fig. 1) through the multiple conductors 5 and 6. In Fig. 2 the subscriber's line multiples 1—2 terminate in contacts 7—8 of an automatic selector switch S. This switch is of a type well understood in the automatic telephone art in which movable contacts or wipers such as 7 and 8 are carried on a shaft 10 biased in a given normal 110 115 120 125 130

position by a spring or other suitable means not shown and arranged to be stepped around by a stepping magnet 11 through a stepping pawl 12 and a ratchet 13. Also, as is usual with such switches, it is provided with a dog 14, arranged to be thrown out of engagement with the ratchet 13 and to throw the stepping pawl 12 out of engagement when the dog is tripped by the actuation of the release magnet 15, the energization of the release magnet 15 effecting the tripping of the dog 14 through an extension 16 on its armature 17 pivoted at 18. To hold up the armature extension 16 until the switch has released, a trip detent 19 is provided which is pivoted at 20 and arranged to be held normally out of engagement with the hook 21 on the armature 17 by a cam 22 on the switch shaft which permits the detent 19 to move into operative relation with the hook 21 whenever the switch is in off-normal position. Mounted on the switch shaft 10 are other pairs of wipers 23-24, 25-26, and 27-28. The switch S is provided with a contact bank containing rows of contacts 30, 31, 32 and 33 arranged to be engaged by the switch wipers 7-8, 23-24, etc., successively in the direction indicated by the adjacent arrow, it being understood that while the drawing, which is purely diagrammatic shows the contacts arranged in a straight line they are in practice arranged in a circle concentric with the switch shaft so as to permit the switch arms to sweep across them in the rotation of the shaft. While only three vertical rows of contacts are here shown it is to be understood that they may be more or less in number and that in any case the first few vertical rows of contacts are left blank or disconnected, for example, in the present case the first five, leaving the sixth vertical row of contacts the first ones that are connected with the operating circuits so that the switch must make five steps before effecting any circuit connections, after which the wipers will be moved successively to the sixth, seventh and eighth vertical rows. The purpose of providing this lost motion or blank steps will be made clear in the description of operation. The switch wipers 23-24 connect with the adjacent terminals of the winding 34-35 of a repeating coil 36, the remote terminals of which windings connect to the plate and filament of the audion tube 37. The switch wipers 25-26 connect to the grid and filament of the tube 37, while the wipers 26 and 28 form the terminus of the filament of the tube 37. The wiper 27 is connected to the multiple test wire 3, leading into Fig. 1. The horizontal row of contacts 30 are connected as multiple pairs, the upper and lower members being connected respectively to the remote terminals of the coils 38 and 39 of the repeating coil 36 through the conductors 40 and 41, the conductor 41 connecting with the coil 39 through a line supply relay 42, shunting resistance 43 and conductor 44. The adjacent terminals of the coils 38 and 39 are connected to the plus and minus side of the exchange common battery B through conductors 45 and 46, and bus conductors 47 and 49, respectively. In the horizontal row of contacts 31, the sixth, seventh and eighth pairs are connected individually to the batteries B⁶, B⁷, and B⁸ respectively. In the horizontal row of contacts 32, the sixth, seventh and eighth pairs are connected, respectively, to the different program transmitting sets P⁶, P⁷, and P⁸, the lower contacts of the sixth, seventh and eighth pairs being connected respectively to the bus wires of filament batteries F⁶, F⁷, and F⁸ respectively. In the horizontal row of contacts 33 the upper members of each pair are connected in multiple to the conductor 49 which supplies battery current for the test by its connection through repeat relay 50, conductor 46 and bus 48 to the central office common battery B. The lower contact members of the horizontal row 33 are connected individually to the upper bus wires of the different filament batteries F⁶, F⁷, and F⁸. Thus the batteries B⁶, B⁷, and B⁸, the program transmitters P⁶, P⁷, and P⁸, and the filament batteries F⁶, F⁷, and F⁸, are associated individually with the sixth, seventh and eighth vertical rows of contacts, respectively. The stepping magnet 11 and release magnet 15 have their windings connected in multiple, one side to ground and the other side through conductor 51 to an impulse wire 40 leading into Fig. 1 where it terminates in a front or normally open contact 52 of the line relay L', which contact is engaged by the armature 53 connected through wire 54 to the exchange common battery B. The conductor 51 is also connected in multiple to a normally open contact 55 engaged by the armature 56 of the relay 50, the armature 56 being connected by way of conductors 46 and 48 to the exchange common battery B. The repeat relay 50 is controlled by the sleeve relay 42 through the armature 57 which is arranged, as shown, to close a shunt around the winding of the relay 50 by way of resistance 58, armature 57 and conductor 59. The subscriber's broadcast receiving set A² is similar in all respects to the usual booster coil, common battery telephone receiving set, except that the switchhook is replaced by a spring jack J² arranged, upon the insertion of a plug, to close the line circuit through the line multiples 5-6, winding 60 of the booster coil 61, transmitter 62 and automatic dial 63, while connecting the subscriber's broadcast, telephone receiver 64 across the line multiple 5-6 in series with the coil 61-65 and telephone condenser 66. The program trans-

ductors 40 and 41, the conductor 41 connecting with the coil 39 through a line supply relay 42, shunting resistance 43 and conductor 44. The adjacent terminals of the coils 38 and 39 are connected to the plus and minus side of the exchange common battery B through conductors 45 and 46, and bus conductors 47 and 49, respectively. In the horizontal row of contacts 31, the sixth, seventh and eighth pairs are connected individually to the batteries B⁶, B⁷, and B⁸ respectively. In the horizontal row of contacts 32, the sixth, seventh and eighth pairs are connected, respectively, to the different program transmitting sets P⁶, P⁷, and P⁸, the lower contacts of the sixth, seventh and eighth pairs being connected respectively to the bus wires of filament batteries F⁶, F⁷, and F⁸ respectively. In the horizontal row of contacts 33 the upper members of each pair are connected in multiple to the conductor 49 which supplies battery current for the test by its connection through repeat relay 50, conductor 46 and bus 48 to the central office common battery B. The lower contact members of the horizontal row 33 are connected individually to the upper bus wires of the different filament batteries F⁶, F⁷, and F⁸. Thus the batteries B⁶, B⁷, and B⁸, the program transmitters P⁶, P⁷, and P⁸, and the filament batteries F⁶, F⁷, and F⁸, are associated individually with the sixth, seventh and eighth vertical rows of contacts, respectively. The stepping magnet 11 and release magnet 15 have their windings connected in multiple, one side to ground and the other side through conductor 51 to an impulse wire 40 leading into Fig. 1 where it terminates in a front or normally open contact 52 of the line relay L', which contact is engaged by the armature 53 connected through wire 54 to the exchange common battery B. The conductor 51 is also connected in multiple to a normally open contact 55 engaged by the armature 56 of the relay 50, the armature 56 being connected by way of conductors 46 and 48 to the exchange common battery B. The repeat relay 50 is controlled by the sleeve relay 42 through the armature 57 which is arranged, as shown, to close a shunt around the winding of the relay 50 by way of resistance 58, armature 57 and conductor 59. The subscriber's broadcast receiving set A² is similar in all respects to the usual booster coil, common battery telephone receiving set, except that the switchhook is replaced by a spring jack J² arranged, upon the insertion of a plug, to close the line circuit through the line multiples 5-6, winding 60 of the booster coil 61, transmitter 62 and automatic dial 63, while connecting the subscriber's broadcast, telephone receiver 64 across the line multiple 5-6 in series with the coil 61-65 and telephone condenser 66. The program trans-

mitting devices P^6 , P^7 , and P^8 are preferably radio receivers of a type adapted to receive radio broadcast matter from near or distant points and amplify and relay the same at audio frequency on to their respective bus wires 66, 67 and 68 respectively, the amplification being effected in any suitable manner such as by detection and audio amplification or a combination of radio amplification, detection and audio amplification, the audio amplification being preferably limited to one stage so as to allow a second stage of audio amplification to be made between the busses and the ultimate receiver. In this case the ultimate receiver is the subscriber's broadcast receiver 64 and the second stage of amplification is effected through an audion tube 37 individual to each line.

In the operation of the arrangement shown in Figs. 1 and 2, the subscriber at station A' operatively connects his broadcast receiving or extension set A^2 to the line by inserting the receiver plug P^2 in the jack J^2 which connects his receiver 64 across the line multiples 5 and 6 through the booster coil windings 60-65 and condenser 66 in series, and closes a path for direct current between the multiples 5 and 6 through coil 60, lower spring of jack J^2 , transmitter 62, and automatic dial 63. This energizes the subscriber's line relay at the central office in the usual manner by current from the central office common battery B, which energizing circuit may be traced from the grounded side of central office common battery B, conductor 68, right hand winding of line relay L' , line conductor 69, to subscriber's substation A' , line multiple 5, to subscriber's broadcast receiving sets A^2 (Fig. 2), coil 60, transmitter 62, contacts of dial 63, conductor 6, 70, left hand winding of line relay L' and back to the battery B. Energization of the line relay energizes the line lamp L^2 by closure of a local circuit which may be traced from the battery B through elements 54, L^2 , 71, 68 and back to battery B. This causes the line lamp L^2 at the telephone operator's switchboard to glow, but only for a moment as the subscriber wanting broadcast service will immediately operate his dial to break and make his line circuit a certain number of times according to the particular program he desires which breaks and makes will cause his line lamp to flicker instead of glowing steadily and so indicate to the telephone operator that the subscriber is not calling for a telephone connection but is automatically setting up his connection for broadcast reception. As the dial 63 is of the well known type used in automatic telephony and well understood in the art, it will not be necessary to describe the same here in detail and it suffices to say that it operates automatically to effect one or a series of breaks of brief dura-

tion in the line circuit according to the setting of the dial each time it is set and released. The first closure of the line and energization of the line relay L' completes an energizing circuit for the stepping magnet 11 (Fig. 2) which may be traced from the free side of the common battery B through circuit elements 54, 53, 52, 4, (into Fig. 2), 51 to stepping magnet 11 and release magnet 15 in multiple and thence through ground back to the grounded side of battery B. It is to be noted here that the release magnet 15 is made sluggish in its action so that it will not respond to the energizing current until after a lapse of time much longer than the interval between the breaks and makes of the subscriber's dial 63 so that when the subscriber first closes his circuit, as just described, the stepping magnet 11 will first operate to step the switch 9 around one step releasing the detent 19 after which, the time period of the release magnet 15 having lapsed, this magnet will actuate its armature to move the hook 21 up into engagement with the detent 19 and the extension 16 into engagement with the dog 14 which disengages the dog from the ratchet 13 and also throws the pawl 12 out of engagement with the ratchet, thus causing the switch to release and return to normal position whereupon the cam 22 will throw the detent 19 out of engagement with the hook 21 and leave the armature 17 free to return to normal position when the magnets become deenergized. In the case of a call for telephone connection this deenergization of the magnets would occur when the telephone operator, in answering, inserts the plug P' in the jack J' which would operate the line cut-off relay L^3 in the usual manner causing the line relay L' to retract its armature 53 and open the circuit of the stepping and release magnets 11 and 15. To prevent the subscriber's broadcast selector switch 9 from being stepped around and connecting broadcast matter on to his line due to one or more accidental breaks in his line circuit while the subscriber is waiting for telephone operator service, the selector switch 9 is provided with several blank contacts preceding those representing the different broadcast programs. In the present illustration the first five contacts are left blank, the series of active contacts beginning with those of the sixth vertical row, as indicated in Fig. 2, where the blank contacts are not shown, it being understood that the switch must make five steps before its wipers engage the first set of active contacts. Thus if the subscriber, while waiting for an operator should accidentally, momentarily open his line or impatiently operate his switchhook a few times, the connector switch would simply step around over a few of the blank contacts and release as before described when the operator plugged

in with her answering plug. Returning now to the subscriber's selection of a desired broadcast program, the subscriber, shortly after the initial closure of his line effected 5 by his insertion of the plug P^2 in the jack J^2 , and before the line lamp has been energized sufficiently long to indicate a telephone call to the operator, sets his dial to a number corresponding to the number of the broad- 10 cast program he wishes to receive, which in the present case would be some number above five, and permits the same to release producing a number of breaks corresponding to the setting of the dial. Assuming the setting to 15 be eight, the dial upon release will cause the line circuit to be momentarily opened eight times. The first five breaks in the line circuit will cause the armature 53 of the line relay to open and close its connection with the 20 contact 52 five times, thus stepping the selector switch around to the fifth contact, the period of closure of the contacts 52-53 being sufficiently brief to prevent actuation of the release magnet 15. Upon the sixth mo- 25 mentary break and subsequent make of the line circuit, the switch 9 will step on to the sixth or first vertical row of active contacts whereupon the line cut-off relay L^3 will be energized and the control of the stepping 30 magnet 11 transferred from the line relay to the ring side relay 42 of the switch circuit. The energizing circuit of the cut-off relay L^3 may be traced from the common battery B (top of Fig. 2), bus wire 48, conductor 46, 35 winding of repeat relay 50, conductor 49, upper member of the sixth contact of horizontal row 33, switch wiper 37, conductor 3, into Fig. 1 line cut-off relay L^3 , conductor 69 to grounded side of the common battery B. Energization of repeat relay 50 causes 40 its armature 56 to engage the contact 55 thus maintaining the stepping magnet 11 energized by current from battery B through circuit elements 48, 46, 56, 55, 51, 11 to ground and back to battery B, while the 45 energization of the cut-off relay L^3 (Fig. 1) disconnects the line relay L' in the usual manner which becoming deenergized releases its armatures 71-53, extinguishing the line 50 lamp and opening the circuit through conductor 4. Simultaneously with the energization of the cut-off relay L^3 and repeating relay 50, the sleeve relay 42 is energized by current from the common battery B through 55 the circuit elements 48, 46, 39, 42, 41, lower member of the sixth contact in the horizontal row 60, switch wiper 8, line multiple 2 into Fig. 1, line wire 70, multiple wire 6, into Fig. 1, through circuit elements 63, 62, 60, 5 65 into Fig. 2, 69, 1, into Fig. 2, 7, 40, 38, 45, 47, and back to the grounded side of the common battery B. Energization of ring side relay 42 causes its armature 57 to be attracted and complete a shunt around the winding of repeat relay 50 by way of circuit 70 elements, 58, 57 and 59, which shunt causes the relay 50 to become deenergized and retract its armature 56 opening the circuit of the stepping magnet 11 and causing it to return to normal ready for the next step. 75 The next or seventh momentary break in the subscriber's line circuit, which follows immediately, effects a momentary release of the armature 57 of sleeve relay 42 which causes a momentary energization of the repeat relay 50 which in turn effects a momentary closure of the contacts 56-50 and a momentary energization of the stepping magnet 11 to step the switch wipers around to the seventh vertical row of contacts. The energizing circuit of the stepping magnet may be traced from the common battery B through circuit elements 48, 46, 56, 55, 51, and 11 back to the grounded side of battery B. Similarly, the next or eighth momentary break 80 in the line causes the stepping magnet 11 to be again momentarily energized and step the switch wipers around into engagement with the eighth vertical row of contacts. 85

After the eighth momentary break in the line circuit the subscriber's dial 63 comes to rest and maintains the line circuit closed. The line now being closed, the ring side relay 42 is maintained energized which maintains the repeating relay 50 deenergized by 90 virtue of the closure of the shunt around its winding which in turn maintains the circuit of the stepping and release magnets 11 and 15 open at the contacts 55-56. The switch wipers thus come to rest on the eighth vertical row of contacts, maintaining the input terminals of the subscriber's line tube 37 in operative connection with the bus wires 68 of the program transmitter P^8 through switch wipers 25-26 and the eighth pair of 95 contacts in the horizontal row 32. Current is supplied to the output or plate circuit of the tube 37 from battery B^8 , individual to the program transmitter P^8 , over circuit elements 72, 73, 23, 74, 34, plate of tube 37, 100 filament of tube 37, 75, 35, 76, 24, 77, 78, back to battery B^8 . As the coil 36 is a repeating coil of the well known type having the four windings 34, 35, 38, 39 on a common magnetic core the output or plate circuit of the tube 37 is coupled to the subscriber's line through the coils 38-39 which are included in series in the subscriber's line circuit as hereinbefore traced. The filament circuit of the subscriber's audion tube 37 105 may be traced from filament battery F^8 , individual to the program transmitter P^8 , over the circuit elements 79, lower member of bus wire 68, 26, filament of audion tube 37, 110 filament of tube 37, 75, 35, 76, 24, 77, 78, back to battery B^8 . As the winding 60 of the booster coil 61 at the subscriber's broadcast receiving set A^2 is included in series in the line, the broadcast matter coming thereover is repeated in the winding 65 which reproduces 115 120 125 130

the signal in the subscriber's receiver 64 over a circuit which may be traced from 65, through circuit elements 66, 63, 62, and through the receiver 64 back to winding 65 by way of the plug and jack connection P^2-J^2 . As the battery supply relay 42 is held energized during the subscriber's use of his line for receiving broadcast, should a telephone operator test one of his multiple jacks in the usual manner before establishing a connection therethrough to his line, instead of the ordinary busy test of a click in the ear, she will receive a special tone test which will indicate that the line is not busy for telephone use but is being used for the reception of broadcast so that if the call is an emergency one the operator may plug in regardless of the busy condition. Thus a special tone test is effected by the usual tone test apparatus indicated in Fig. 2 as consisting of the inductance 87 connected in series with a circuit breaker 88 and inductively related to the coil 58 in series in the test circuit. The energizing circuit of the coil 87 may be traced from the common battery B through the circuit elements 48, 46, 87, 88, back through ground to the battery B.

When the subscriber wishes to discontinue the broadcast reception he withdraws the plug P^2 which opens the line circuit at the jack contact 89. This deprives the sleeve relay 42 of current whereupon its armature 57 is retracted removing the shunt from the repeating relay 50 which thereupon becomes energized and closes the circuit of both the stepping magnet and the relay magnet through connection of the armature 56 with contact 55. This circuit may be traced from battery B through the circuit elements 48, 46, 56, 55, 51, 11 and 15 in multiple to ground and back to the battery B. After the brief lapse of time required for the operation of the release magnet 15 this magnet attracts its armature which brings the extension 16 into engagement with the dog 14 to trip the same which in turn trips the pawl 12 allowing the switch to return to normal, hook 21 engaging the detent 19 which holds the armature 17 in its actuated position during the restoring movement of the switch and until the switch reaches the normal position whereupon the cam 22 operates to disengage the detent 19 from the hook 21 and permit all parts of the switch to return to the normal position shown. When the switch in restoring moves its wipers off the sixth vertical row of contacts the circuit repeat relay 50 is broken at the wiper 27, and the repeat relay 50 deenergizing opens the circuit of the magnets 11 and 15 at the contact 55-56. This puts all the circuits and apparatus in the normal condition shown in Figs. 1 and 2.

For metering the subscriber's use of the radio broadcast service on a basis of time

use, a meter controlling actuator 90 (Fig. 2) is arranged to control the subscriber's telephone meter M (Fig. 1) through the operative connection of the switch circuits of Fig. 2 with the subscriber's central office line 70 terminal circuits. This control circuit may be traced from the meter generator 91 (Fig. 2) through commutator 90, switch 92, bus wire 93, switch 94, wire 49, the upper member of one of the contacts in the horizontal row 33, wiper 27, test wire 3, into Fig. 1, wire 95, high voltage winding 96, of the meter M, to ground and back to the grounded side of the meter generator 91 (Fig. 2). When the meter armature 97 is retracted a sufficient distance to close the contact 98 the low voltage winding 99 of the meter M is closed thus aiding in the further attraction of the armature and the actuation of the meter as well understood in the art, which actuation will be repeated at intervals according to the intervals of the closing and opening of the circuit meter commutator 90. These periodic registrations of the meter during use of the broadcast apparatus will of course be added to those produced by the actuation of the usual, telephone operator's metering key 100, so that the subscriber's use of the broadcast service is charged in the same units as that of the telephone use and the amount of service represented by the unit charge varied according to the speed of operation of the commutator 90. Where the service to some of the lines is to be given free the switch 94 100 individual to the line is opened and where the service is to be given free to all or a group of lines the switch 92 is opened to disconnect the commutator from the bus 93 common to all or a group as the case may be. 105

Referring now to Fig. 3, this is similar to Fig. 2, just described, except that the line multiples 1-2 are permanently connected to the outside terminals of the coils 38 and 39 and the battery connection to the inside terminals of these coils controlled through the upper pair of wipers 7-8 of the switch 9, and the horizontal row 30 of the switch bank contacts. Another difference is that the repeat relay is omitted and the stepping of the switch, after connection with the active contacts, controlled through a back or normally closed contact of the ring side relay 42 connected to battery through an off normal switch 101 controlled by a cam 102 on the switch shaft 10 arranged to maintain the off normal switch closed only during engagement of the switch wipers with one of the sets of active contacts that is, from the sixth vertical row on. As this is a modification of the switching circuit illustrated in Fig. 2 and intended to operate in place thereof, it is to be read in connection with Fig. 1. The conductors 1, 2, 3, 4, 5 and 6 of Fig. 3 tie on to the similarly numbered 120 125 130

conductors of Fig. 1. In the operation of this circuit arrangement when the subscriber operates the dial 63 at his broadcast receiving set A², to effect the eighth successive 5 momentary breaks in his line circuit, the first six cause the line relay to close the contact 52-53 six times which in turn effects six successive energizations and deenergizations of the stepping magnet 11, the successive 10 impulses being as before described, of too brief duration to cause actuation of the release magnet 15. The energizing circuit of stepping magnet 11 may be traced from battery B (Fig. 1) through circuit elements 53, 52, 4, into Fig. 3, 51, 11, and through ground back to battery B. This causes the 15 switch 9 to step around to the sixth vertical row of bank contacts whereupon the cut-off relay L³ (Fig. 1) is energized by current 20 from battery B (Fig. 3) through the circuit elements 58, upper contacts of row 33 of the switch bank contacts, 27, 3, L³, 68, to ground and back to battery B. At the same time battery is supplied to the subscriber's 25 line in series with the ring side relay 42 over a path which may be traced from battery B (upper part of Fig. 3) through upper members of row 30 of the switch bank contacts, circuit elements 7, 140, 39, 42, 2, 70, to subscriber's station and back by way of 69, 1, 38, 30 141, 8, lower contacts of row 30, back to battery B. The seventh break in the line, effected by the subscriber's dial 63, effects a 35 momentary deenergization of the sleeve relay 42 whose armature falling back produces a momentary closure of the circuit of the stepping magnet 11 whose energizing circuit may now be traced from battery B (Fig. 3), through wiper 7 to wire 140, as 40 before traced, and thence through off normal switch 101, the cam 102 now having moved into a position to close the same, thence through circuit elements 103, 104, 105, 51, 11, and through ground back to battery B. 45 Similarly upon the eighth break in the line circuit, the switch 9 is stepped again, this time onto the eighth vertical row of contacts, which connects the input circuit of the subscriber's line tube 37 onto the program 50 bus wires 68 through the eighth pair of contacts in row 32 and switch wipers 25-26. The switch wipers 23-24 engaging the eighth pair of contacts, connect the battery B⁸, individual to the Number 8 program, 55 through conductors 74 and 76 through the windings 34 and 35 of the repeat coil 36 to the output or plate circuit of the subscriber's line tube 37, while the switch wipers 7 and 8 maintain the connection with the 60 battery B through the multiple contacts of row 33 and so supply current over the subscriber's line as before traced. Also, as in Fig. 2, the filament circuit of the subscriber's line tube 37 will be supplied with current 65 from the filament battery A⁸ individual to

the Number 8 program, the connections for this being the same as that of Fig. 2. Also, as in Fig. 2, the cut off relay, busy test and meter control circuit 3 is completed through wiper contact 27. The circuit of the cut off 70 relay may be traced from battery B (Fig. 3) through the circuit elements 58, upper member of the engaged contact in row 33, 27, 3, into Fig. 1, L³, 68, and back to battery B. The tone test is imposed upon this circuit by 75 the coupling of the tone test coil 87 with the coil 58 included in the test circuit in the usual manner well understood in the art, while the meter actuating source 91 and commutator 90 are connected with this circuit 80 through conductor 142. The circuit of the meter actuating current may thus be traced through the source 91, through the circuit elements 90, 142, 143, 27, 3, into Fig. 3, 95, meter M, to ground and back to the source 85 91.

In Fig. 4, is shown diagrammatically, a switch circuit which is a simplified form of the circuit arrangement of Fig. 3 in which the number of switch wipers are reduced to 90 a minimum by delegating the control of certain circuits which are common to all the programs, to a cam actuated switch operable to maintain said circuits closed only during the engagement of the switch wipers with 95 the program contacts. In this, as in the other switch arrangements previously described, the contact bank of the switch is provided with several vertical rows of blank contacts, for example five in number, not 100 shown, for the purpose of permitting the switch to be stepped around several steps without effecting connection with any program transmitters. Parts of the present switching arrangement which are similar to 105 and perform the same function as corresponding parts in the previously described switching arrangement, are similarly numbered. For example, the battery supply for the output circuit of the subscriber's line 110 tube or relay 37 is furnished through wipers 23 and 24 and the top row of bank contacts, the connection between the input circuit of the subscriber's line relay tube 37 and the program source is effected through wipers 25 and 26 and the second horizontal 115 row of bank contacts, the filament current supply is furnished through wipers 26 and 29 and their associated contacts, and the metering circuit is connected through wiper 120 27 and its associated contact, with the meter actuating source. All of these circuits are to be connected with sources individual to a program and so their control is delegated to the wipers which change connection with 125 each step of the switch. Thus, circuit connections which are not individual to a program such as the connections effected through the multiple line conductors 1-2, 130 test conductor 3, and impulse conductor 4,

are controlled through the cam operated switch 145. This switch is controlled by the cam 146 carried by the switch shaft 10 to maintain the contacts open when the switch 5 is in its normal position or has moved into a position in which its wipers are on any of the blank contacts, and will maintain its contacts closed in any position of the switch 10 in which the switch wipers are in engagement with a set of the program contacts. Another feature characteristic to the present 15 switch arrangement is the position of the individual meter IM individual to the switch circuit so as to meter only the use of the subscriber's line for broadcast reception. As 20 with the other switching diagram, the present diagram is to be read in connection with Fig. 1, the conductors 1, 2, 3, and 4 of Fig. 4 tying onto the conductors 1, 2, 3 and 4 of Fig. 1 respectively.

In the operation of this arrangement, the impulses sent over wire 4 from the subscriber's line relay in Fig. 1, pass directly to the stepping magnet 11 through conductor 146 25 until the switch has been stepped around to the sixth row of contacts whereupon the contacts of switch 145 are closed, the sleeve relay 42 energized in series with the subscriber's line and the cut off relay in Fig. 1 30 energized to disconnect the line relay, which now causes the further stepping of the switch to be controlled through the sleeve relay as a repeating relay responding to breaks in the subscriber's line circuit. The 35 circuit of the cut off relay (Fig. 1) may be traced from battery B (Fig. 4), supervisory lamp 147, conductor 148, contact of switch 145, conductor 3, into Fig. 1, cut off relay L³, conductor 68 to ground and back to battery 40 B. The energization of the cut off relay L³ causes the line relay L' to become deenergized and open the circuit through the impulse conductor 4 as before described in connection with Figs. 1 and 2. At the same 45 time the cut off relay is deenergized to bring about the disconnection of the circuit through conductor 4, the ring side relay 42 is energized in series with the subscriber's line by a circuit which may be traced from 50 battery B through the circuit elements 39, 42, 2, 70, over the subscriber's line and back by way of circuit elements 69, 1, 38, to battery B. Upon the next momentary break 55 in the subscriber's line circuit the ring side relay 42, being energized in series therewith, is momentarily deprived of current which causes a momentary retraction of its armature, which in turn closes the circuit of the stepping magnet 11 which may be now 60 traced from battery B through the circuit elements 104, 105, 146, 11, to ground and back to battery B. Thus, each momentary break in the subscriber's line circuit causes 65 the switch to make one step. When the switch comes to rest with its switch wipers

on the vertical row of contacts corresponding to the desired program, the ring side relay 42 remains energized maintaining a shunt around the lamp 147 through resistance 149 thus extinguishing the signal light. 70 This is the operating position of the switch, and during the maintenance of this connection, assuming the switch wipers to be in contact with the vertical row of bank contacts associated with the number 7 program, the individual, broadcast service meter will be intermittently energized in a circuit which may be traced from the meter energizing source 91, through commutator 151, switch 152, upper member of the bottom pair 80 of contacts in the eighth row, switch wiper 27, conductor 153, meter IM to ground and back to the source 91. It will be noted here that by movement of the switch arm 152 to its right hand contact the meter will be controlled through the commutator 151 instead of 152. As these commutators are arranged to close and open the circuit at different periodicity, the meter will be operated at a different rate thus making a different charge 90 per hour for the service. For the purpose of assigning different rates to different programs the switches 152 and 154 included in the meter circuits of the different programs, respectively, are arranged, as shown, with 95 different contacts connected with the different commutators 150 and 151, respectively. Thus, with the meter control commutators 150 and 151 associated with different programs, the subscriber's service charges as recorded by his broadcast meter IM will vary according to the particular program taken by him. To enable the operator or supervisor having charge of a number of switching devices like the present one, to listen in on 100 the subscriber's line in the usual manner as in a telephone operator's cord circuit for the purpose of communicating with the subscriber, a listening key K' is provided arranged to connect a suitable listening set, not shown. The subscriber may apprise such supervisor of his wish for some special service by making several successive momentary breaks in his line circuit much in excess of that required for the stepping of the 110 switch to any of the sets of program contracts during which the supervisor noticing the apparent constant flickering of the supervisory lamp 147, will operate the listening key K' to ascertain the wants of the subscriber. To enable the supervisor to call 115 the subscriber during the connection of his line through the switch mechanism, a special signaling key 'S' is provided which is arranged to connect the inductance coil 154 120 across the subscriber's line, which coil is inductively connected with the special tone signal circuit and thus puts the signal on the line to be heard in the subscriber's loud speaker. To enable the subscriber to receive 125

other broadcast items not on the programs to which his switch has access, the last vertical row of contacts in the switch have their program contacts such as 155 connected to 5 a special program trunk 156 terminating in a jack 157 situated before what may be termed a special program operator who has access to trunks leading to other stations providing different broadcast items, and who 10 is also provided with means, such as telephone plugs forming the terminals of such trunks, for connection of any of said trunks to the special program contacts 155 through the jack 157, and short trunk 156. When 15 the subscriber desires such special items he signals the supervisor in charge of the broadcast service by sending in the excessive number of breaks to signal the supervisor through actuation of the lamp 147 as before 20 described, the extra number of breaks in the line circuit causing the switch to step around to the last vertical row of contacts and there come to rest, which disconnects the subscriber's line from all of the regular programs 25 and connects it through the switch wipers 25—26 and special programs contacts 155 to the trunk 156 terminating in the jack 157. The supervisor listening in through use of the key K' may now ascertain the wants 30 of the subscriber and communicate the same to the special program operator over a suitable order circuit not shown. The special program operator may then give the subscriber the program or item desired, by inserting the terminal plug of the appropriate trunk in the jack 157. This trunking arrangement for supplying the special programs from other stations will be clearly understood from an inspection of Figs. 5 35 and 6.

In Fig. 5 is diagrammed a portion of a general system of broadcast distribution comprising a master station A, district stations B, subscribers' central stations C, and 45 subscribers' substations D, the relation of the stations A, B and C being the same as that described in my copending application Serial No. 746,357, filed October 28, 1924. It suffices here to say that the station A is a 50 master station for the system having means for originating or relaying broadcast matter to the B stations either by radio or over trunk lines, such as 158 and 159, that the B stations have means for originating or re- 55 laying broadcast matter from the A station or stations outside the system to C stations, and that the C stations, together with the subscribers' substations D are provided with means in the form of the circuits herein pre- 60 viously described in detail, for originating or relaying broadcast matter from the B stations to the subscribers' stations D. The broadcast matter is originated or received from the other stations and put onto the program contacts of the subscriber's selector 65

switches by any known or other suitable form of apparatus symbolized at P⁶, P⁷, and P⁸ in Figs. 2, 3 and 4.

In Fig. 6 is shown diagrammatically, the special trunking system enabling a subscriber at a D station to extend his line beyond his associated central station either directly, or through other stations of the system to some particular station for the purpose of receiving the broadcast program there originated or there available through suitable relay apparatus, for example, station B². For this purpose, the special program operator at the C station is provided with a link circuit LC capable of connecting a trunk 70 terminal jack 160 with the subscriber's special jack 157 (the same as 157 of Fig. 4) through a detector and amplifier unit DA. The jack 160 forms the terminal of a trunk 75 161 terminating in the "B" station B' in the output circuit of a line amplifier tube 137 whose input circuit terminates in a jack 162. Similarly, the station B' is provided with the circuit LB' arranged to connect the jack 162 with the jack 163 to an amplifier unit 80 IA, the jack 163 forming the terminal of a trunk 159 which terminates in the output circuit of a line tube 237 at the "A" station, the input circuit of which tube terminates in the jack 164. At the "A" station 85 is provided an amplifying link circuit LA the same as that of station B' arranged to connect the jack 164 with a jack 165 forming the terminal of a trunk 158 terminating in a line tube 337, and jack 159 90 at station B² in the same manner as that of the trunks 159 and 161. At the station B² is provided a link circuit LB² similar to those at stations A and B' and arranged to connect the jack 159 with the broadcast program apparatus 166 which may be a local source of broadcast matter or suitable relay device capable of relaying broadcast from some other station. Thus, with the trunking 95 system so described the subscriber at a D station may extend his line to the broadcast transmitter 160 of the station B² over the trunking connection which may be traced from 160 through the trunking elements LB², 159, 337, 158, 165, LA, 164, 237, 159, 110 163, LB', 162, 137, 161, 160, LC, 157, 37 to subscriber's station D. In the present illustration this broadcast matter is transmitted from the station B² over the trunks 158, 115 159, and 161 by carrier current, which is detected and amplified in the detector amplifier unit DA at the C station and from thence transmitted to the subscriber's station at audio frequency or in the form of the original modulations, the amplifier units IA 120 at the stations B², A, and B' being operable on the intermediate or carrier current frequency. In Figs. 5 and 6, the trunks 161, 159 and 158 are symbolical of a plurality of trunks which afford trunking distribution 125 130

out from any of the stations to several C stations directly or through other stations. It is also to be noted that the outgoing terminal of each trunk line is provided with 5 a line tube similar to that of the subscriber's line tube which acts as an amplifier or relay so that throughout the several links, the line tubes or relays will operate to effect gradual amplification throughout the distribution 10 thus avoiding the losses and the necessity for currents of large magnitude incident to long distant distribution without the use of increments of power between the source and destination. It will be obvious that where 15 conditions are favorable, the amplifiers IA at the intermediate stations A, B', etc. may consist of but one step or may even be omitted or replaced by suitable coupling means, the line tubes or relays 137, 237, etc., being 20 relied upon for effecting the necessary amplification.

The arrangement of circuits and apparatus for carrying out the idea of distribution with gradual amplification or increments of 25 power at a broadcast distributing central is diagrammatically shown in Fig. 7, where a source of audio signals is indicated at 167, the signals of which are distributed through a transformer 168 and a group of several 30 amplifier tubes 169 in multiple to the input side of a suitable coupling means such as the audio transformer 170, the output side of which distributes through several amplifier tubes 37 to as many trunks or line circuits 35 173. The line circuits 173 represent the subscriber's lines such as the subscriber's line 69—70 of Fig. 1, while the amplifier tubes 37 represent the individual line tubes or relays such as 37 of Figs. 2, 3, etc. It will 40 thus be seen that with this arrangement the amount of power in any of the intermediate circuits may be considerably less than the total amount of power distributed.

It is to be noted that the broadcast matter 45 may if desired be put on the program contacts of the switch banks in the form of modulated carrier current, in which instance the subscriber's line tubes 37 would be preceded each by a detector tube or other detecting means individual to the line.

Reference is hereby made to copending application, Serial No. 47,550, filed August 55 1, 1925, as a division out of this application, containing claims to the service metering and differential metering which are disclosed but not claimed herein.

What I claim is:

1. In a system of radio broadcast distribution, a central station, subscribers' stations 60 and wire lines interconnecting them, means at the central station to receive broadcast modulated waves, and relay means also at the central station, individual to the lines, for connecting with said broadcast receiving 65 means in common and adapted to relay the

modulations received from said broadcast connection, to the subscribers over their wire lines individually.

2. The system claimed in claim 1, with means at the subscribers' stations for individually controlling the line relaying means, 70 over the wire lines.

3. The system claimed in claim 1, with the line relaying means consisting of individual vacuum tubes, or valves, one for each line, 75 at the central station, and means whereby the input sides of said line tubes may be connected in common to receive the output of the central office transmitting or relay apparatus, and the output side of each line 80 tube may be simultaneously and separately connected to its own line.

4. The system claimed in claim 1, with the line relaying means consisting of individual vacuum tubes, or valves, one for each 85 line, at the central station, and means whereby the input sides of said line tubes may be connected in common to receive the output of the central office transmitting or relay 90 apparatus, and the output side of each line tube may be simultaneously and separately connected to its own line, together with means at each subscriber's station to control the connection of his own line tube at 95 central.

5. The system claimed in claim 1, with the line relaying means consisting of individual vacuum tubes, or valves, one for each line, at the central station, and means whereby the input sides of said line tubes may be connected in common to receive the output of the central office transmitting or relay apparatus, and the output side of each line tube may be simultaneously and separately connected to its own line, together with means 100 at each subscriber's station to control the connection of his own line tube at central, and to disconnect the same when not receiving. 105

6. In a system of broadcast distribution, a central station and subscribers' stations, and wired line circuits interconnecting them, a transmitter at the central station adapted to send out broadcast matter and a plurality of 110 vacuum tubes or valves, one for each subscriber's line at the central station, having their input or grid terminals adapted for connection to said transmitter in common and their output or plate terminals separately connected to their respective lines 115 individually. 120

7. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapted for connection to said transmitter in com- 125 130

mon and their output or plate terminals separately connected to their respective lines individually, together with sources of current supply at the central station for all said tubes.

8. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapted for connection to said transmitter in common and their output or plate terminals separately connected to their respective lines individually, together with switching means at the central station for connecting said line tubes to said transmitter, and means at subscribers' stations for controlling said switching means over their wire lines.

9. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapted for connection to said transmitter in common and their output or plate terminals separately connected to their respective lines individually, together with switching means at the central station for connecting said line tubes to said transmitter, and means at subscribers' stations for controlling said switching means over their wire lines to connect the tubes for receiving and to disconnect the same at will.

10. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapted for connection to said transmitter in common and their output or plate terminals separately connected to their respective lines individually, together with sources of current supply at the central station for all said tubes, and means controlled by the subscribers over their wired line circuits to connect said current sources to the tubes for energizing the same.

11. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapt-

ed for connection to said transmitter in common and their output or plate terminals separately connected to their respective lines individually, together with automatic switching means controlled by the subscribers over their line circuits for connecting and disconnecting their line tubes.

12. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapted for connection to said transmitter in common and their output or plate terminals separately connected to their respective lines individually, together with automatic switching means controlled by the subscribers over their line circuits for connecting and disconnecting their line tubes to and from the central office transmitter.

13. In a system of broadcast distribution, a central station and subscribers' stations, and wired line circuits interconnecting them, a transmitter at the central station adapted to send out broadcast matter and a plurality of vacuum tubes or valves, one for each subscriber's line at the central station, having their input or grid terminals adapted for connection to said transmitter in common and their output or plate terminals separately connected to their respective lines individually, together with automatic switching means controlled by the subscribers over their line circuits for connecting and disconnecting their line tubes to and from the central office transmitter on one side and to and from their lines on the other.

14. In a system of broadcast distribution, having a central station and a plurality of subscribers' stations, a primary source of broadcast electrical waves, and means at the central station to relay the same in stages increasing in both volume amplification and in number of units of amplification, the last set of units being equal in number to the subscribers' stations together with means to bring into service units of the last or line set in response to the call subscribers for broadcast service, whereby the final or line stage of amplification will be exactly proportionate to the number of lines taking such service.

15. In a system of broadcast distribution, having a central station and a plurality of subscribers' stations, a primary source of broadcast electrical waves, and means at the central station to relay the same in stages increasing in both volume amplification and in number of units of amplification, the last set of units being equal in number to the subscribers' stations, and individually appropri-

ated to their use, one to each, together with means to bring into service units of the last or line set in response to the call of subscribers for broadcast service, whereby the final 5 or line stage of amplification will be exactly proportionate to the number of lines taking such service.

16. In a system of broadcast distribution, a central station and subscribers' stations 10 and wired line circuits interconnecting them, a plurality of broadcasting transmitters at the central station, and individual broadcast repeating relay units also at the central station, one for each subscriber's line circuit, 15 with switching means to interconnect each subscriber's relay unit interchangeably with the central station transmitters.

17. In a system of broadcast distribution, a central station and subscribers' stations 20 and wired line circuits interconnecting them, a plurality of broadcasting transmitters at the central station, and individual broadcast repeating relay units also at the central station, one for each subscriber's line circuit, 25 with switching means to interconnect each subscriber's relay unit interchangeably with the central station transmitters, said switching means being selectively controlled by the subscribers.

30 18. In a system of broadcast distribution, a central station and subscribers' stations and wired line circuits interconnecting them, a plurality of broadcasting transmitters at the central station, and individual broadcast 35 repeating relay units also at the central station, one for each subscriber's line circuit, with switching means to interconnect each subscriber's relay unit interchangeably with the central station transmitters, and con- 40 trolling means at the subscribers' stations for said switching means.

19. In a system of broadcast distribution, a central station and subscribers' stations and wired line circuits interconnecting them, 45 a plurality of broadcasting transmitters at the central station, and individual broadcast repeating relay units also at the central station, one for each subscriber's line circuit, with switching means to intercon- 50 nect each subscriber's relay unit interchangeably with the central station transmitters, said switching means being located at the central station, and controlling means at the subscribers' stations for said switch- 55 ing means.

20. In a system of broadcast distribution, a central station and subscribers' stations and wired line circuits interconnecting them, a plurality of broadcasting transmitters at 60 the central station, and individual broadcast repeating relay units also at the central station, one for each subscriber's line circuit, with switching means to intercon- 65 nect each subscriber's relay unit inter- 70

changeably with the central station trans- 65 mitters, said switching means being individual to the subscribers' relay units and lines, and controlling means therefor at the subscribers' stations, acting through the wired line circuits. 70

21. In a system of broadcast distribution, a central station and subscribers' stations and wired line circuits interconnecting them, a plurality of broadcasting transmitters at the central station, and individual broadcast 75 repeating relay units also at the central station, one for each subscriber's line circuit, with switching means to interconnect each subscriber's relay unit interchangeably with the central station transmitters, said switching means comprising a selector switch individual to each line, containing terminals of the output circuits of the central office transmitters. 80

22. In a system of broadcast distribution, 85 a central station and subscribers' stations and wired line circuits interconnecting them, a plurality of broadcasting transmitters at the central station, and individual broadcast repeating relay units also at the central station, one for each subscriber's line circuit, 90 with switching means to interconnect each subscriber's relay unit interchangeably with the central station transmitters, said switching means comprising a selector switch individual to each line, containing terminals of the output circuits of the central office transmitters, and other terminals adapted to connect the line tube to the line circuit. 95

23. In a system of broadcast distribution, 100 a central station and subscribers' stations and wired line circuits interconnecting them, a plurality of broadcasting transmitters at the central station, and individual vacuum 105 tube relay units also at the central station, one for each subscriber's line circuit, with switching means to interconnect each subscriber's relay unit interchangeably with the central station transmitters, said switching means comprising a selector switch individual to each line, containing terminals of the output circuits of the central office transmitters, and other terminals adapted to connect the line tube to the line circuit 110 and to close the energizing circuit of the 115 tube.

24. In a system of radio broadcast distribution, a central broadcasting system and subscribers connected thereto by means of 120 wired line circuits, centralized means for receiving modulated radio waves and for detecting the same to produce audio frequency modulations, individual audio amplifier and relay tubes one associated with each subscriber's line, means for supplying current 125 to said tubes, and means to connect the same on their input sides to said centralized detector means, and means to separately con-

nect each one on its output side with its associated line whereby distribution is effected over the subscribers' lines, with volume amplification proportionate to the number of lines receiving, and without interference.

25. In a system of radio broadcast distribution, a central station and a plurality of subscribers' stations with wired line circuits interconnecting them, broadcast relaying or transmitting apparatus, telephone switching apparatus at the central station for interconnecting the lines for conversation, radio switching apparatus independent in its operation, adapted to connect the lines for broadcast receiving to said relaying or transmitting apparatus, a responsive device at the central station for each subscriber's line and means at each subscriber's station for operating the same to effect preliminary selection as between the telephone switching apparatus and the radio switching apparatus, and means at a subscriber's station for controlling said responsive device and thereafter adapted to control said radio switching apparatus.

26. In a system of radio broadcast distribution, a central station and a plurality of subscribers' stations with wired line circuits interconnecting them, broadcast relaying or transmitting apparatus, telephone switching apparatus at the central station for interconnecting the lines for conversation, radio switching apparatus independent in its operation, adapted to connect the lines for broadcast receiving to said relaying or transmitting apparatus, a responsive device at the central station for each subscriber's line and means at each subscriber's station for operating the same to effect preliminary selection as between the telephone switching apparatus and the radio switching apparatus, and means at a subscriber's station for controlling said responsive device, together with further responsive means associated with the radio switching apparatus, becoming active after said preliminary selection and adapted to respond directly to the subscriber's

control for actuating said radio switching apparatus.

27. In a system of radio broadcast distribution, a central station and a plurality of subscribers' stations with wired line circuits interconnecting them, telephone switching apparatus at the central station for interconnecting the subscriber's lines for conversation, broadcast receiving and transmitting apparatus at the central station, switching apparatus also at the central station for connecting the subscribers' lines individually with said broadcasting apparatus for receiving modulations therefrom, a signal circuit for the telephone switching apparatus, a signal circuit for said broadcast switching apparatus, a responsive device at the central station controlled by the subscriber to effect preliminary selection as between said signal circuits, and means associated with said broadcast switching apparatus adapted to be directly controlled by the subscriber and to control said broadcast signaling circuit, after said preliminary selection.

28. In a system of radio broadcast distribution, a central station and subscribers' stations and wired line circuits interconnecting them, telephone switching apparatus at the central station for interconnecting the lines for conversation, broadcast switching apparatus adapted to connect the lines to centralized broadcast receiving, relaying and transmitting apparatus, a signal circuit for the telephone switching apparatus, a signal circuit for the broadcast switching apparatus, and a line relay connected with the subscriber's line responsive to subscriber control normally controlling both of said signal circuits with means to disable said line relay after preliminary selection of the broadcast switching circuit and to render the same thereafter directly responsive to the subscriber control.

In testimony whereof I hereunto affix my signature.

EDWARD E. CLEMENT.
